UNITED STATES PATENT OFFICE.

WILLIAM A. SCHOENBORN, OF HENSEL, NORTH DAKOTA.

POTATO CUTTER.

Application filed July 19, 1922. Serial No. 576,058.

To all whom it may concern:

Be it known that I, WILLIAM A. SCHOENBORN, a citizen of the United States, residing at Hensel, in the county of Pembina 5 and State of North Dakota, have invented new and useful Improvements in Potato Cutters, of which the following is a specification.

This invention relates to a potato cutter 10 and has for its primary object the provision of a device particularly designed for cutting seed potatoes into desired sizes for planting without bruising, mashing or mutilating the potatoes.

15 An object of the invention is to provide a potato cutter as specified which is simple in construction and may be manufactured and sold at a relatively low cost.

With these and other objects in view the 20 invention will be better understood from the following detailed description taken in connection with the accompanying drawing wherein:

Fig. 1 is a side elevation partly in section 25 of the improved potato cutter.

Fig. 2 is a horizontal sectional view taken on the line 2—2 of Fig. 1.

Fig. 3 is a vertical sectional view on the line 3—3 of Fig. 1.

30 Fig. 4 is a detailed view of the plunger employed in the cutter structure.

Referring more particularly to the drawing the improved cutter comprises a supporting body 1 having a rectangular central opening 2 which slidably receives therein the plunger 3. The plunger structure 3 is hollow as clearly shown at 4 in Fig. 1 of the drawing, having its upper inner end rounded to fit a potato as indicated at 5 and the depending sides 6 of the plunger are provided 35 with a plurality of longitudinally spaced vertically extending slots 7 provided for re-

ceiving the transverse connecting blades 8 carried by the supporting base 1 and extending transversely of the recess 2. A single blade 9 extends longitudinally of the recess 2 intermediate its sides so that the potato 5 will be cut into a plurality of relatively small pieces when it is forced downwardly upon and passed the knives 8 and 9 by downward movement of the plunger 3. The plunger 3 has a pair of upstanding ears 10 formed thereon which are pivotally connected to depending boss 11 formed upon the handle 12 intermediate the ends of the handle. The handle 12 is pivotally connected at one end as shown at 13 to bosses 14 formed upon the supporting body or base 1. As clearly shown in Fig. 1 of the drawing it will be noted that the pivot pin 15 which connects the plunger 3 to the boss 11 travels in an arcuate slot 16 so as to permit pivotal movement of the handle 12 and vertical reciprocal movement of the plunger 3 without causing binding action of the plunger against the walls of the opening 2.

It is, of course, to be understood that the invention may be constructed in various other manners and the parts associated in different relations and therefore, I do not 70 desire to be limited in any manner except as set forth in the claim hereunto appended.

Having thus described my invention what I claim is:

A potato cutter comprising a body having 75 a centrally arranged opening, knives arranged across the opening, a hollow plunger having sides arranged in sliding engagement with certain walls of the opening during the entire travel of the plunger, and 80 a handle for reciprocating said plunger.

In testimony whereof I affix my signature.

WILLIAM A. SCHOENBORN.
